TRAFFIC SIGN DEVICE

Andrew O. Wittreich, Tenafly, N. J.

Application October 26, 1950, Serial No. 12,749

Term of patent 14 years

(Cl. D72—1)

To all whom it may concern:

Be it known that I, Andrew O. Wittreich, a citizen of the United States of America, residing in Tenafly, in the county of Bergen and State of New Jersey, have invented a new, original, and ornamental Design for a Traffic Sign Device, of which the following is a specification, reference being had to the accompanying drawings, forming a part hereof.

Fig. 1 is a side view of a traffic sign device, showing my new design;

Fig. 2 is a top view of the device; and

Fig. 3 is a cross section taken on the line 3—3 in Fig. 1.

The dominant features of my design are shown in solid lines in the drawing.

I claim:

The ornamental design for a traffic sign device, as shown and described.

ANDREW O. WITTREICH.
